UNITED STATES PATENT OFFICE

116,432

DESIGN FOR A PAIR OF SPECTACLES

George P. Miller, Dover-Foxcroft, Maine

Application January 16, 1939, Serial No. 82,368

Term of patent 14 years

To all whom it may concern:

Be it known that I, George P. Miller, a citizen of the United States, residing in Dover-Foxcroft, in the county of Piscataquis and State of Maine, have invented a new, original, and ornamental Design for a Pair of Spectacles, of which the following is a specification, reference being had to the accompanying drawing, forming part thereof.

Fig. 1 is a plan view of a pair of spectacles; and

Fig. 2 is a face view of the same with the temples omitted showing my new design, the essential features of which reside in the configuration of the frames because of the way in which they are attached to the lenses.

I claim:

The ornamental design for a pair of spectacles, substantially as shown and described.

GEORGE P. MILLER.
